(57) **CLAIM**

The ornamental design for a part of a hot chocolate maker
as shown and described.

DESCRIPTION

1.1 : Top

1.2 : Perspective

1.3 : Side

1.4 : Side

1.5: Top view of the whisk element of the part for a hot
chocolate maker shown separately for ease of illustration
and clarity of the design.

1.6: Perspective view of the whisk element of the part for a
hot chocolate maker shown separately for ease of illustration
and clarity of the design.

(Continued)

The broken lines show portions of the part for a hot chocolate maker that form no part of the claimed design.

1 Claim, 6 Drawing Sheets
